(57) **CLAIM**

The ornamental design for a massage apparatus, as shown and described.

DESCRIPTION

FIG. 1 is a perspective view of a massage apparatus showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another perspective view showing the massage apparatus; and,

FIG. 9 is still another perspective view showing the massage apparatus.

The broken lines shown in the figures are for the purpose of illustrating portions of the massage apparatus, which form no part of the claimed design.

1 Claim, 9 Drawing Sheets
